UNITED STATES PATENT OFFICE.

JOSEPH KORN, OF NEWARK, NEW JERSEY.

CREASE-RETAINING DEVICE FOR HATS.

1,352,975.

Specification of Letters Patent. Patented Sept. 14, 1920.

Application filed October 11, 1919. Serial No. 330,000.

To all whom it may concern:

Be it known that I, JOSEPH KORN, a citizen of the United States, residing at Newark, in the county of Essex and State of New Jersey, have invented certain new and useful Improvements in Crease-Retaining Devices for Hats; and I do hereby declare the following to be a full, clear, and exact description of the invention, such as will 5 enable others skilled in the art to which it appertains to make and use the same, reference being had to the accompanying drawings, and to characters of reference marked thereon, which form a part of this specification.

This invention has reference, generally, to improvements in crease-retaining devices for hats; and, the present invention relates, more particularly to an improved device 20 to be applied inside the crown of a hat of the creased or soft-crown type, and means for the purpose of retaining the crease therein.

The present invention has for its principal object to provide a novel and simply constructed device of the general character hereinafter more particularly set forth which will be as light as possible and inexpensive to manufacture, and is easily applied, the device being provided with resilient engagement members or wings adapted to be located upon the opposite sides of the crease of the hat and being adapted to be compressed against the said 35 sides of the crease, with a view of providing marginal retaining means which will positively engage the opposite surface-portions of the crease of the hat, so that the said crease-retaining device is not apt to work 40 loose and drop off.

These and other objects will be fully elaborated in and will be evident and understood from the following description of the present invention.

The said invention consists, primarily, in the general construction of crease-retaining device for hats hereinafter more fully set forth; and, the said invention consists, furthermore, in the general arrangement and 50 combination of the various parts of the said device, all of which will be more fully described in the said specification, and then finally embodied in the clauses of the claims

which are appended to, and which form an essential part of the said specification.

The invention is clearly illustrated in the accompanying drawings, in which:

Figure 1 is a transverse vertical section of a creased hat showing in connection therewith, and also in section, my novel 60 crease-retaining device in its engagement with the opposite surface-portions of the crease formed in the hat; and Fig. 2 is a perspective view of the said crease-retaining device, detached from the hat, said view 65 being made on an enlarged scale.

Similar characters of reference are employed in the said above-described views to indicate corresponding parts.

Referring now to the said drawings, the 70 reference-character 1 designates a soft-type hat, the upper portion of which is inwardly creased, as at 2, in the usual manner. Over this crease, upon the inside of the hat crown, is fitted the novel crease-retaining device 3, 75 said device being bent into U-shaped cross-section, substantially as illustrated in said Fig. 1 of the drawings, and the said device showing one embodiment of the principles of the present invention. The said retaining 80 device 3 which is usually made from relatively thin sheet metal, such as aluminum, but which may be made of any other suitable material, comprises a pair of wings 4 which are oppositely placed, as shown, said wings 85 being joined by a shorter central portion 5. When placed within the hat, the device 3 is folded longitudinally of this short central portion 5, so as to bring the wings 4 against the inner side-portions 6 of the crease 2, 90 substantially as shown in said Fig. 1 of the drawings, and in which position the said device can be laterally squeezed, in the direction of the arrows indicated in said Fig. 1, so as to securely clamp the said crease and 95 cause the same at all times to retain its proper position.

The outer-edge portions of the wings 4 of the said crease-retaining device are preferably flared, as at 6, to form narrow flanges 100 which surround the said wings and which adds stiffness to the device, by resisting bending and buckling strains and also prevents chafing of the cloth or other fabric of the hat at the edges of the clamping portions of the said wings 4.

Suitable retaining means in the form of inwardly extending retaining projections 7 with which the wings 4 are provided prevent the device from slipping or falling off, 5 when the device has been pressed into its retaining position upon the creased portion of the hat. The crowns receive considerable bending and distortion, and that although the clamping device is provided with retaining 10 projections, as 7, the clamping portions of the wings 4 very often work loose.

For use in such hats, it has been found advisable and practical to provide the clamping portions of the wings 4, at or near 15 their marginal edge-ports with a grasping or holding means, as 8, and the preferred form of such grasping or holding means being made in lines of diamond-shaped projections, as clearly indicated in Fig. 2 of 20 the drawings, the various points of which are easily forced into the creased fabric, as will be clearly understood from an inspection of Fig. 1 of the drawings.

It will be evident, however, that while 25 the longitudinally extending marginal clamping or holding means 8, shown in Fig. 2, is the preferred form, still I am fully aware that other forms of such clamping or retaining means may be employed; and, I 30 therefore do not limit my present invention to the exact form of marginal clamping or retaining projections as herein shown.

I claim:—

1. A crease-retaining device for hats comprising a pair of wings joined by a central portion, said device being substantially U-shaped in cross-section so as to be adapted to embrace the crease of a hat, combined with a continuous line of inward projections 35 immediately adjacent the gripping edges of said wings, said retaining means being

adapted to be embedded in the surface-ports of the crease of the hat so as to retain the said creasing-device in position.

2. A crease-retaining device for hats comprising a pair of wings joined by a central portion, said device being substantially U-shaped in cross-section so as to be adapted to embrace the crease of a hat, combined with marginal retaining means extending 45 inwardly from the gripping edges of said wings, said marginal retaining means consisting of a series of inwardly extending pointed projections adapted to be embedded in the surface-ports of the crease of the 50 hat so as to retain the said crease-retaining device in position.

3. A crease-retaining device for hats comprising a pair of longitudinally extending wings joined by a relatively short center 60 portion, said center portion being bent upon itself to cause said wings to cause the device to assume a U-shaped cross-section adapted to embrace the crease of a hat, combined with marginal retaining means extending 65 from and at the marginal gripping edges of said wings, said marginal retaining means consisting of a series of inwardly extended pointed projections adapted to be embedded in the surface-ports of the 70 crease of the hat so as to retain the said crease-retaining device in position, and additional retaining projections extending inwardly from said wings.

In testimony that I claim the invention set forth above I have hereunto set my hand this 9th day of October, 1919.

JOSEPH KORN.
